[57] CLAIM

The ornamental design for a tape cartridge data storage system, as shown and described.

DESCRIPTION

FIG. 1 is a top, front, right side perspective view of a tape cartridge data storage system showing our new design;

FIG. 2 is a front elevational view thereof;

FIG. 3 is a top plan view thereof;

FIG. 4 is a right side elevational view thereof, the left side being a mirror image;

FIG. 5 is a top, front, right side perspective view of a second embodiment of our design;

FIG. 6 is a front elevational view thereof;

FIG. 7 is a right side elevational view thereof, the left side being a mirror image.

The grid is shown in broken lines in FIGS. 1, 3 and 5 for illustrative purposes only and forms no part of the claimed design.
